UNITED STATES PATENT OFFICE.

HERBERT M. SMITH, OF GREAT BARRINGTON, MASSACHUSETTS, ASSIGNOR TO STANLEY INSULATING COMPANY, OF GREAT BARRINGTON, MASSACHUSETTS, A CORPORATION OF MAINE.

APPARATUS FOR FILLING-RECEPTACLES OR THE LIKE.

1,397,061.

Specification of Letters Patent.

Patented Nov. 15, 1921.

Application filed September 30, 1918. Serial No. 256,281.

To all whom it may concern:

Be it known that I, HERBERT MILLS SMITH, a citizen of the United States, residing at Great Barrington, in the county of Berkshire and State of Massachusetts, have invented certain new and useful Improvements in Apparatus for Filling-Receptacles or the like, of which the following is a specification.

10 This invention relates to method and apparatus for filling and compressing finely divided insulating material into the vacuous space of such an article as is shown in the United States patent to William Stanley No. 1,071,817 for a heat-insulated receptacle.

As set forth in a co-pending application for patent, it is highly desirable that the finely divided insulating material of such 20 a receptacle should be compressed into the vacuous space to such an extent as will result in the maximum heat-insulating value and maximum of mechanical support for the spaced shells. This compression can of course be accomplished manually, but the 25 operation thus conducted is tedious and cannot in the nature of things be uniformly and evenly done, and it is of course most desirable that these bottles should be uniform in 30 every respect when they are finished.

I have accordingly devised a method and apparatus for filling and compressing finely divided heat-insulating material into a vacuous space by means of automatically 35 operative mechanism, utilizing for the purpose centrifugal force and incidentally providing for the substantial dehydration of the insulating material before it is packed into place.

40 Other objects of the invention more or less broad than those stated above will be in part obvious and in part specifically referred to in the course of the following description of the elements, combinations, arrangements 45 of parts and applications of principles constituting the invention; and the scope of protection contemplated will appear from the claims.

In the accompanying drawings which are 50 to be taken as a part of this specification and in which I have shown a form of apparatus which is adapted for the carrying out of my process, Figure 1 is a front elevation

with parts in section of an apparatus for the carrying out of my invention; and Fig. 55 2 is a view partly in section and partly in elevation taken on the line 2—2 of Fig. 1 looking in the direction of the arrows.

Referring to the numerals on the drawings, there is shown at 4 a hopper or reservoir which is to contain a supply of finely divided insulating material, this hopper having a lower compartment 5 through which passes an endless bucket conveyer 6 traveling over sprockets 7, 8, 9 and 10, of which the 60 bracket 10 may be the driving sprocket, receiving its power through a belt or sprocket chain 11, and the sprocket 7 may be mounted in an ordinary take-up device 12 whereby any slack in the conveyer may be taken up 70 from time to time. Opening out of the lower end of the compartment 5 is a revolving cylindrical retort 14, having one end rotating within the compartment 5 and the other end indicated by the numeral 15 rotating in a bearing formed at the top of a standard 16. This revolving cylindrical retort extends inside of a heating furnace 17, which may conveniently be heated by gas, the gas pipe being shown at 18 and the 80 air pipe for supporting combustion shown at 19. This furnace is supported on suitable standards 20, which also afford bearings for a shaft 21 having a driving pinion 22 meshing with a gear wheel 24 which is 85 secured to the revolving cylindrical retort 14 as to a shaft, so that the rotation of the wheel 24 causes the rotation of the cylindrical retort. At the other end of the shaft 21 there is another driving pinion 25 which 90 meshes with a pinion 26 on the end of a stub shaft 27, driven by means of a pulley 28 and driving belt 29. The other end of the shaft 27 is supported in bracket 30, and there is a large driving pinion 31 mounted 95 on this shaft 27 which engages with a driving pinion 32 for the centrifugal wheel. The hub of this centrifugal wheel is indicated at 34 and rotates in ball bearings 35 supported on brackets 30 and 36. The hub 100 34 of the centrifugal wheel is elongated on both sides; at one side it surrounds one end of a tube 37, the other end of which is held in the bearing at the top of the standard 16, forming a continuation of, but separate 105 from the adjacent end of the revolving

cylinder 14. The extension at the other end of the hollow hub 34 is indicated at 38, and beyond this end of the hollow hub there is a box 40 having a valved bottom 41. In 5 this box is also mounted the sprocket 9 for the endless conveyer, and there is an opening in the front of the box to allow of the movement through it of the endless conveyer, this opening being indicated at 42. 10 The space between the box opening 42 and the end 38 of the hub is guarded by a curtain of flame made by gas burners 44.

The bearing for the end 15 of the revolving cylinder 14 is formed as an inlet for a 15 suction pump pipe 45, this inlet being indicated at 46, and the pump itself at 47. The pump is driven in any convenient way and from its shaft 48 the sprocket 10 may be driven through sprocket chain 11. From 20 the construction described and as appears from the drawing it will be seen that the conveyer 6 is arranged to travel slowly through the compartment 5 containing the insulating material, carrying quantities of 25 insulating material out of the compartment into and through the constantly revolving cylinder 14, where it is subjected to the heat of the surrounding furnace 17, thence to the other end of the rotating cylinder and into 30 the stationary extension 37 of the rotating cylinder. At this point the heated material is subjected to the suction of the pump 47. In order that the material itself may not be 35 drawn into the suction pipe the inlet will be guarded preferably by a quantity of steel wool or the like indicated at 48' suitably held in position at the inlet, this permitting the passage of air but preventing the withdrawal of the insulating material. Thence 40 the material is carried through the extension 37 into the interior of the hollow hub 34 of the centrifugal wheel. This wheel as best indicated in Fig. 2, is provided with a plurality of radially disposed tubular seat members 50, each opening into the interior of the 45 hub and adapted to receive a vacuum bottle 51, with the open bottom thereof presented toward the bottom of the hub. The other end of the bottle is received in an end clamp 50 52 movable radially toward and from the corresponding seat member 50, such movement being controlled by means of a screw 54 operating in the rim 55 of the wheel. The manner of holding the vacuum bottle is 55 clearly shown in Fig. 1, the outer shell of the bottle appearing at 56 and the inner shell at 57 with the vacuous space at 58 opening downwardly toward the hub, the vacuous space being closed at the other end 60 of the bottle. The driving connections are so arranged that whereas the endless conveyer and the rotating cylinder move at a slow rate of speed, the centrifugal wheel rotates at a very high rate of speed so that as 65 the insulating material is brought into the

bottom of the hub and subjected to the centrifugal force generated by the rapidly rotating wheel the insulating material is thrown with great force toward the rim or perimeter of the wheel, finding a path 70 through the several tubular seating members 50 and the vacuous spaces 58 of the bottles which are virtually an extension of the seating members. Thus the insulating material is rapidly and uniformly and firmly compressed into the vacuous spaces of the bottles, the endless conveyer bringing fresh supplies of substantially heated and dehydrated material until the bottles are filled, when the machine is stopped and the bottles removed. 75 In order that the air initially contained within the bottles may not interfere with compression into the vacuous spaces of the bottle of the insulating material each bottle may be provided near the neck end of the vacuous space, with a tiny vent indicated by the numeral 60, through which the air from the interior of the bottle may escape as the insulating material is packed in. This vent will of course have to be closed immediately 80 the bottle is filled, and at the same time the bottom closure will have to be put on the bottle so that the insulating material will not have an opportunity to absorb moisture from the air. The furnace 17 serves to heat 85 the material and drive off any moisture, which is positively removed through the suction pipe 45 before the material arrives at the centrifugal wheel; and the flame curtain produced by the burners 44 prevents the 90 entry into the hollow hub from the other end of any moist air. Any particles of material which may travel through the hollow hub will fall into the bottom of the box 40 and may be removed from time to time by 95 means of the door or closure 41. 61 indicates a hood for collecting products of combustion from the furnace 17, which go off through a pipe 62.

I claim:

1. In a device of the kind described, a centrifugal member for supporting a receptacle to be loaded including a central portion open at both ends for the passage of a conveyer, an endless conveyer passing through the central portion of the centrifugal member for supplying finely divided material, the centrifugal member being provided with passages opening from the central portion thereof into the receptacles. 110

2. In a device of the kind described a centrifugal member for supporting a receptacle to be loaded including a central portion open at both ends for the passage of a conveyer, an endless conveyer passing through the central portion of the centrifugal member for supplying finely divided material, the centrifugal member being provided with passages open from the central portion thereof into the receptacles, and means for 115 120 125 130

dehydrating the finely divided material carried by the conveyer before it reaches the centrifugal member.

3. In a device of the kind described a centrifugal member for supporting a receptacle to be loaded including a central portion open at both ends for the passage of a conveyer, and endless conveyer passing through the central portion of the centrifugal member 10 for supplying finely divided material, the centrifugal member being provided with passages open from the central portion thereof into the receptacles, and means for heating and dehydrating the finely divided 15 material carried by the conveyer before it reaches the centrifugal member.
4. In a device of the kind described, a centrifugal member for supporting a receptacle to be loaded including a central portion open 20 at both ends for the passage of a conveyer, an endless conveyer passing through the central portion of the centrifugal member for supplying finely divided material, the centrifugal member being provided with passages opening from the central portion thereof into the receptacles, means for heating and dehydrating the finely divided material carried by the conveyer before it reaches the centrifugal member, and means for preventing 25 access of humid atmosphere to the finely divided material after it has been heated and before it is deposited in the receptacle.
5. In a device of the kind described, a hopper, an endless conveyer passing through 30 the hopper, a rotating cylinder through
- which the conveyer passes, said cylinder communicating with the hopper, a heating apparatus surrounding the cylinder, a wheel provided with a hollow hub and hollow seat members extending radially from the hub, a conduit leading from said cylinder into the hub, suction means connected to said conduit, means for holding receptacles on the hollow seat members, and means for driving the conveyer and rotating the cylinder and 40 the wheel.
6. In a device of the kind described, a centrifugal member having a hollow hub, a series of passages radiating therefrom and means for clamping over each passage a receptacle to be filled, a hopper, a cylinder communicating at one end with the hopper and at its opposite end with the hollow hub of the centrifugal member, a heating means for the cylinder, and an endless conveyer 50 passing through the hopper, the cylinder and the hollow hub for feeding filling material from the hopper through the cylinder to the hub.
7. In a device of the kind described, a centrifugal member having a hollow center portion and means for securing thereon receptacles to be filled, a hopper, and an endless conveyer passing through the hopper and center portion of the centrifugal member 55 for feeding filling material from the hopper to the centrifugal member.

In testimony whereof I affix my signature.

HERBERT M. SMITH.
